[57] ABSTRACT

A programmable process and production control center features a complete system of built-in selectable input and output interfaces, internal selectable electronic clocks, control subsystems, and a programmable read-only-memory card reader. In governing the operation of the control center, the control subsystem responds to a combination of input signals. As a selective read-only-memory, a specially formatted card in a card reader enables and determines response to a plurality of external, internal and time signals in order to determine the development of the combination of input signals. Included in the overall arrangement is a wide range of selection with respect to types of inputs and types of outputs as well as permitting choice between numerous different inter-coordinated responses.

PROGRAMMABLE PROCESS AND PRODUCTION CONTROL SYSTEMS

The present invention pertains to programmable process and production control systems. More particularly, it relates to programmable process control systems which exhibit capability of complex control function while yet exhibiting simplicity of set up and operation.

A typical process in which automatic control is desired is a flow-solder station for electronic printed circuits. It is desired to use an optimum amount of flux and to complete as many printed boards per minute as practically possible. However, the duration and amount of flux applied, and the proper rate of the conveyor, varies with different types of printed boards. Without automatic control of some sort, optimum operation requires that a skilled individual be present to reset each of the station functions each time a new board is to be processed. Of course, that is an uneconomical approach.

Quite apparently, a general purpose computer may be programmed so as to respond to information indicating the kind of board under process at any given time and thereupon serve to control the station function as ordered by its programming. However, this approach requires the inclusion in the overall system of peripheral or interface equipment between the process stations and the computer. It also requires the services of a trained computer programmer in order to feed the computer with the necessary information in the proper language.

It is, accordingly, a general object of the present invention to provide a programmable process and production control center which overcomes the aforesaid disadvantages and deficiencies.

A more specific object of the present invention is to provide a controller which requires no external input/output or interface equipment and no knowledge of computer programming in order to obtain satisfactory operation.

Another object of the present invention is to provide a controller in which control functions may be changed merely by the insertion of an appropriately punched or otherwise marked program card.

A further object of the present invention is to provide a controller which features a wide range of flexibility and adaptability.

Still another object of the present invention is to provide a controller that utilizes, as a programmable read-only-memory, an inexpensive tabulation card that is replaceable, reusable and economically disposable.

A still further object of the present invention is to provide a controller with a memory that is totally accessed instead of being only address accessed.

In accordance with the invention, a programmable process and production control center includes means for developing an output signal in response to the occurrence of magnitude of one of time, number of events, and change of character together with means for governing the operation of the development means in response to a combination of input signals. Selectively fixed totally-and-simultaneously accessed passive self-decoding read-only memory means responds to a plurality of incoming signals for defining and determining the development of the combination of input signals. Various features include internal options of types of input and output signals, highly flexible selectable ex-

pansion of needed functions and both internal and external interconnection and interdependence of various functions under determination of the memory means.

The inventive features which are believed to be novel are set forth with particularity in the appended claims. The invention, together with further objects and advantages thereof, may best be understood, however, by reference to the following description taken in conjunction with the accompanying drawings in the several figures of which like reference numerals identify like elements and in which:

FIG. 1 is a front elevational view of the exterior of a programmable process and production control center;

FIG. 1a is a separated isometric view of a card reader specifically implemented for use in the control center of FIG. 1;

FIG. 1b is an enlarged fragmentary cross-sectional view of the implemented form of card reader shown in FIGS. 1 and 1a;

FIG. 1c is a front view of a decoding platen incorporated into the card reader of the preceding figures;

FIG. 2 is an enlarged rear elevational view of the same control center;

FIG. 3 is a functional diagram of one embodiment of the present invention;

FIG. 4 is a functional diagram of an enhanced embodiment of the present invention;

FIG. 5 is a pictorial representation of a control card utilized in connection with the embodiments of the earlier figures;

FIG. 6 is a functional block diagram of an embodiment of the present invention;

FIG. 7 illustrates the input control logic employed in the system of FIG. 6;

FIG. 8 depicts a block diagram of one version of the embodiment of FIG. 6;

FIGS. 9a, 9b and 9c are schematic diagrams of different input options included in connection with the embodiments of the previous figures;

FIG. 10 is a schematic diagram of a portion of the apparatus shown in FIG. 8;

FIG. 11 is a schematic diagram of another portion of the apparatus shown in FIG. 8;

FIG. 12 is a schematic diagram of still another portion of the apparatus shown in FIG. 8;

FIG. 13 is a schematic diagram of a further portion of the apparatus shown in FIG. 8;

FIGS. 14a, 14b, 14c and 14d are schematic diagrams of various output options available in connection with the apparatus of the preceding figures;

FIG. 15 is a schematic diagram of yet another portion of the apparatus of FIG. 8;

FIG. 16 is a schematic diagram of a still further portion of the apparatus shown in FIG. 8; and

FIG. 17 is a schematic diagram of a final portion of the apparatus depicted in FIG. 8.

In order more readily to understand and appreciate details which will follow, initial consideration will be directed to an external view of the apparatus, reference also being made to certain features of flexibility and to various kinds of input and output signals which desirably are to be received or produced. Thus, FIG. 1 depicts the front panel of a presently preferred version of the subject programmable control center. Included on the front panel are a card reader 20, a key-operated main-power switch 22 and a sub-panel 24 in which are mounted a plurality of push buttons 26 distributed in an

array of four columns and four rows. Card reader 20 has a locking lever 27. An indicator sub-panel 28 displays nine illuminated legends. A plurality of light-emitting diodes are distributed in an array 29 of six columns and four rows for indicating counter states.

In essence, the control center is a special purpose electronic digital control system. While using computer circuits and principles, the system concept eliminates the complexity involved in programming and in connecting external equipment to a general-purpose computer. Requiring no peripheral or interface equipment, the control center provides direct outputs in the form of standard control signals or by way of its internal relays. Any particular set or pattern of control functions is changed merely by inserting an appropriate program card in card reader 20. The program card itself is a standard punched tabulator or "computer" card that can be imprinted with the specific functions associated with each punch position. The card serves as a memory in which information is stored in the form of the presence or absence of punches or holes at a variety of specifically-different locations distributed in an array over the card. In the usual manner, the holes may be punched by use of a standard keypunch machine.

Card reader 20 is unique in that it permits static simultaneous reading of all punch positions on a memory card. As shown in FIGS. 1a-1c, the specific manner in which this is implemented is by use of a plurality of electrical spring contacts 20b individually aligned with each of the different possible hole locations in card 20a and distributed in a generally planar bank. Each contact is mechanically biased so as to protrude through a hole aligned with its position and make contact with a decoding platen 20c on the other side of the card. The platen features an array of conductive lands 20d distributed in an appropriate pattern. Thus, a card 20a is disposed between contacts 20b and platen 20c, the contacts being urged toward the platen by spring tension. Upon alignment with an aperture 20d in the card, the corresponding ones of contacts 20b mate and complete electrical connections to the respective conductive lands formed on the platen. Thus, each possible hole location is a potential signal path, and the totality of holes and their absences represent a program. The card reader merely translates various ones of possible incoming signals as determined by the actual hole locations.

In itself, the card reader is quite simple. It includes a platen support 27a hinged along one edge to lever 27 and along the opposite edge to one edge of a contact frame 27b. In use, card 20a is placed into proper position after which lever 27 is manipulated to urge the platen against the card and to lock the reader closed by means of engagement of channels 27c, formed in the upper end portions of lever 27, with pins 27d.

Other known card reader principles may instead be implemented insofar as the system is concerned. For example, the reading process may instead be optical. In that case, a bank of photo-diodes or other light sensitive elements may be distributed in an array to respond to light passing through holes or apertures in a punched card. It is also known to utilize a magnetic storage card, in which case the reader includes a bank of magnetic sensing elements for the purpose of interrogating the card. In the present context, however, magnetic storage is not preferred because it does not permit the untrained operator to inspect the information stored on

the card without the availability of some sort of accessory visual readout device. In any event, the function of the card reader is conventional, as such. It develops a plurality of output signals each uniquely associated with a location on the card and each indicating the "state" of the card at the corresponding location, i.e., signaling whether the card is punched at that location.

As here embodied, the process control center is capable of being operated in three different basic configurations, the choice being dependent upon the user's need. This flexibility is achieved by including the option of employing from one to four complete and essentially identical control subsystems. What may be termed the "minimum" system would include only one such control subsystem (CS). Generally what may be termed the "basic" system would include two control subsystems. A "full" system in the present instance would include four such control subsystems. The available options permit efficient system operation while at the same time permitting lower initial purchase cost by enabling the user to tailor his particular configuration to his own specific needs. At the same time, the control center subsequently may be expanded simply by adding additional modules which are received within the same cabinet.

As depicted in FIG. 1, there are four sets of four push buttons each with each set of push buttons being associated with one control subsystem. If the particular control center includes only one control subsystem, for example, then only the buttons in the first row are operable. Within each set, the button functions are event, start, reset and stop. Moreover, it is punching on the program card which determines whether any or all of the manual pushbutton inputs are to be honored. That is, any one or more of the possible manual input or command signals can be blocked by the punching on the program card in order to prevent erroneous interference with a sequence otherwise programmed on the card. Preferably, latching handle 27, when closed, serves to connect all of the different possible program card functions into the system.

An event is defined as any occurrence that is intended to be counted. For example, if the control subsystem is to count the input from a clock the output of which is in seconds, then each pulse representing one second is an event. Similarly, if the requirement is to count items moving down an assembly line, the passage of each item past a sensing point is an event. In any case, the event push buttons permit the manual input of event signals. These may be used, for example, to permit the adjustment of the count or the testing of the programmed sequence. Each start push button permits the manual initiation of the programmed sequence controlled by the control subsystem associated with that start button. Each reset push button permits the manual resetting of each corresponding programmed sequence, and this may be accomplished either after an automatic or a manual stop. Finally, the stop push buttons each permit the manual stopping of the corresponding programmed sequence at any time.

Input and output connections are available on the rear panel as shown in FIG. 2. Access thus is provided on the rear panel to all possible included control subsystems and with respect to all of the different input and output options that are to be further described. Again, this enables adaptation of the control center to

a wide variety of the user's different individual applications.

In the control center specifically illustrated herein, provision is made to accept four external input signals for each functional category, namely four each of event, start, reset and stop input signals. Additional input signals for the overall center are emergency reset or emergency stop signals and direct input signals that do not enter into the operation of the control center but may be chosen by the control card. Through appropriate punching of the program card, each may be used with any of the different control subsystems. The external input signals come from the user's system. Thus, they may be the output signals, representing process or production status, from sensors of different types such as photo-cell devices, switches or relay closures as well as computer output levels and pulses. Additionally, analog-type inputs are acceptable by use of ancillary options not described in this application. Moreover, the input signals to a given control center may even be output signals from one or more other control centers. In addition, the program card may be punched so that output signals generated internally of the overall control center may also serve as input signals elsewhere in the control center. That is, an output signal from control subsystem CS1 may be interconnected so as to constitute a start signal for control subsystem CS2.

The external input terminal arrangement is in accordance with the labeling included in FIG. 2. As will be further discussed in connection with FIGS. 9a-9c, the external input options are logic, direct current, alternating current and relay or switch. As specifically to be implemented herein, the direct current or DC signal may be at either of 6, 24, or 120 volts, the particular voltage to be accepted being determined by the choice of an input option board to be described further. Similarly, the alternating current or AC input signal may be any of 6, 24 or 120 volts with the particular voltage again being determined by the choice of an input option board. A logic signal or closure or change of any single-pole, double-throw relay or switch also may serve as an input signal to an input option board coupled to an associated input connector. External sources are connected to these options by connectors 30 disposed in a rear access panel 31. Panel 31 is hung from a hinge 32, so that it can be opened, after unlocking clamps 33, to permit access for placement and removal of both input and output option boards to be described further. As illustrated, the input section of the access panel contains five rows of four connectors, providing connective means for event inputs 34, start inputs 35, reset inputs 36, stop inputs 37 and direct inputs 38. Additionally, two connectors 39 are provided for emergency stop and emergency reset functions.

Turning now to the output section of access panel 31, four groupings 40 of four connectors each deliver the basic output signals of the control center. Each of the groupings is associated with a specific control subsystem CS1, CS2, etc. In addition, two groupings 41 of four connectors each provide an expanded set of output signals. These latter connectors, in two groups designated EO1 and EO2, enable expansion of the number of output circuits by use of internally included units which are denominated as expandable output boards. Also included on panel 31 is a group 42 of four connectors that deliver the direct output signals. A connector 43 permits feeding the output of selected system func-

tions, such as the event count of each control subsystem, to auxiliary display units. An example of the latter would be a numeric display that visually presents the event count in decimal numbers. One signal available from receptacle 43 indicates the binary state of the counter internally included with an associated control subsystem; this allows use of a comparatively inexpensive aid in establishing and checking control sequences. Another output signal from receptacle 43 indicates the decimal value of the counter included in an associated control subsystem, thereby providing the additional convenience of a direct reading. Emergency power for use in a power switchover fail-safe mode is fed to the control center by means of a connector 44. The emergency power sources may be batteries or other source of 6 volt and 24 volt direct-current electrical power. Finally included on the rear panel for convenience is a main power receptacle 45 and supply and line fuse receptacles 46.

In general, the operating principle of the overall process and production control center is based upon the fact that almost any process or production system can be described as a sequence of controlled operations that occur either as a function of time interval or as a function of certain events. The control center itself permits the use as an input of either external or internal events or the use of an internal clock to serve as a sequence control. At the same time, starting, stopping, and resetting of any sequence may be controlled by either external or internal input signals. In having up to four identical control subsystems, one such control subsystem can be utilized to control one or more other control subsystems. Consequently, considerable flexibility and rather sophisticated sequence control is available.

To make use of the control center, it is only necessary at the outset to determine what operations and equipment are to be controlled. A program card is then punched to serve as the means for connecting the desired control functions. For this, no knowledge of programming is required; the hole location is easily determined by reference to a pre-prepared diagram, each punch position corresponding to a specific function.

After connecting the control center output terminals to the appropriate equipment, it is then necessary only to insert the program card in order to begin the operation.

As indicated, any one control subsystem may be utilized to act as an independent system; alternatively, it may be interconnected with one or more other control subsystems. A general block diagram of what was termed above as representing a minimum control system is depicted in FIG. 3. At the heart of the operation is a controlled counter arrangement which includes a counter 50 and a control stage 51. Associated with and governed by counter 50 is a comparison circuit 52, labeled circuit-1 in FIG. 3, and three additional comparison circuits indicated in the drawing as circuit-2, circuit-3, and circuit-4. By use of an expandable output board as previously mentioned, counter 50 is also associated with four additional comparison circuits as indicated by the labels circuit-5, circuit-6, circuit-7 and circuit-8. Each such comparison circuit has a desired count as an input. When that count is reached, an output signal is produced. This output is fed to an output option 54, one of the output options previously described as being available to the rear panel, that pro-

duces an output control signal capable of operating external equipment.

Referring again to counter 50, any input to that counter is a level change, or a pulse, that signifies either the occurrence of an event or the passage of an increment of time. The latter input signal comes from an internal clock 56 by way of card reader 20. Card reader 20 has, as other input or incoming signals, those representing start 59, reset 60, stop 61, event 62, emergency reset 63, emergency stop 64, output mode 65, output return 66, count 67 and direct 67a.

Depending upon the holes punched in the program card inserted in card reader 20, the signals from start 59, reset 60, stop 61, emergency reset 63 and emergency stop 64 may be fed to control 51. At the same time, card reader 20 may respond to the program card to route signals from event 62 and clock 56 directly into counter 50. Simultaneously, the program card inserted into card reader 20 directs signals from output mode 65, output return 66 and count 67 directly into comparison circuit 52 and also into the auxiliary other comparison circuits.

The function of output mode 65 may be simply defined. In analogy to switch contacts, the mode is that of normally open or normally closed. Operationally, this means that if, for example, the twenty-four volt direct-current output option is being used and the normally-open mode is selected, then the output signal will be zero until a desired count is reached; thereafter, the closed-mode 24 volt signal will be passed. On the other hand, if a relay option is utilized, then the normally-open contacts of the relay will remain open for the normally-open mode; that is, the relay output corresponds to the output mode. The output mode, therefore, permits selection as to whether an external circuit is to be on or off prior to completion of a count cycle. Output return 66 permits the return of a circuit to its initial output mode. The input of output return 66 comes from another comparison circuit of the same control subsystem.

As indicated previously, each control subsystem may have its output connected to the input of the next. Accordingly, the system of FIG. 3 indicates an internal output signal terminal beyond comparison circuit 52. Similarly, such an internal output signal is available from each of the other comparison circuits.

A more complete control system is depicted in FIG. 4. As indicated, there are a total of four control subsystems tied to a single internal master clock 56. However, each control subsystem can be independently connected to any of the four time increments generated by the master clock. As before in FIG. 3, the initial control subsystem CS-1 includes control stage 51 and counter 50. The latter has direct control of four comparison circuits and expandable control of four more comparison circuits. As to either of the latter two sets of four circuits, there is an output option that permits choice from among four different output signals. Similarly, a control subsystem CS-2 includes the control stage for a counter associated with four basic comparison circuits and an expandable option of four additional comparison circuits. Each such four circuits has its output option to provide a choice from among four different output signals. Also included are two additional control and counter combinations each of which has its own four comparison circuits together with a similar output option choice of different output signals.

As also indicated in FIG. 4, the count out from counter 50 may be employed to serve as an input to the next counter. The succeeding counters are similarly in series for counting. By such a combination, an extremely large maximum count may be achieved. For example, the first control subsystem is herein designed to count to a maximum of 63. With an identical second control subsystem, fed from the first, the count maximum becomes 4,095. The series combination of those two control subsystems with the third control subsystem results in the production of a maximum count of 262,143. By then adding, in series, the fourth control subsystem, the maximum count becomes 16,777,215. These counts permit nominal time maximums, using 15 one control subsystem, of 1 second, 6 seconds, 1 minute and 1 hour for clock increments, respectively, of one sixtieth second, one-tenth second, 1 second and 1 minute. With the use of two control subsystems, the nominal time maximums are 1 minute, 6 minutes, 1 hour and 60 hours for clock increments of the same values. Similarly, a third control subsystem enables nominal time maximums of 1 hour, 6 hours, 60 hours and 150 days, and the use of four control subsystems corresponds to 60 hours, 15 days, 150 days and 24 years, again for the same clock increments. An increment of ten seconds also is available in lieu of one of the increments referred to above.

As already indicated, the internal outputs of each of the individual comparison circuits of each control subsystem may be interconnected or intraconnected. Consequently, each of those output signals may serve in the capacity of any of start, reset, stop, or return within a given control subsystem. Also, each may serve as an event input between different control subsystems.

30 All program center operation is determined at any time by a single program card. FIG. 5 illustrates a preferred form of card which includes printed information that aids in punching and checking. At the same time, it will be recognized that the card in FIG. 5 can be one 35 of very conventional nature. Normally, it includes eighty columns and ten rows of possible punched-hole locations. In addition, there is space for additional information toward the top of the card. Preferably, the 40 card is preprinted to delineate the portions thereof devoted to each of the principally-different areas of concern in governing the operation of the present control system. In addition, only the odd-numbered columns are employed, as indicated by the numbering along the bottom of the card depicted in FIG. 5. This permits 45 practical use of pre-diecut cards that may be punched on-site by an inexpensive hand punch. As also will be seen by inspection of the card, it is divided into ten fields of four columns each. In accordance with the labeling along the top of the program card depicted in 50 FIG. 5, fields 1-4 relate to control subsystems CS-1 through CS-4, respectively. These rows and columns pertain to the control subsystem selections of count, 55 clock and even input. Fields 5 and 6 relate to start information, field 7 relates to start information, field 8 pertains to reset and stop criteria, field 9 pertains to 60 external output mode arrangement and field 10 controls or governs the output return significance. This field 65 also permits selection of the direct inputs to be used with a corresponding direct output. On the card itself, all functions and operations are clearly pre-printed. This permits establishment of the desired control without reference to other information media. The circled

punch positions designate those that are to be punched regardless of the operations desired. The punch positions within boxed areas generally possess a common purpose. Typically, they are alternative inputs one or more of which are to be selected. It will, therefore, be apparent why a pre-printed card especially designed with respect to the disclosed control center is to be desired.

Again by reference to FIG. 5, it will be observed that fields 1-4 are almost identical. Using field 2 as exemplary, Row 12 contains an arrow symbol indicating the punch position for interconnection of control subsystems 1 and 2. Columns 9, 11, 13 and 15 relate respectively to comparison circuits 1, 2, 3 and 4, and rows 0-5 represent respective count values. Each row is pre-printed with the actual associated count value. Rows 6-9 in column 9 pertain to clock period, each time increment being labeled. The same rows in column 11 relate to external events, with the printed numbers referring to the associated input option position. Row 6 in column 13 is connected to the event panel pushbutton, while rows 7, 8 and 9 in that column are used in the selection of an internal event, the printed numbers referring to control subsystems.

Using field 5 as an example of both fields 5 and 6, all of rows 0-5 in all of columns 33-39 pertain to count value as applied to the expandable comparison circuits associated respectively with those different columns. In columns 33-37, row 6 commonly relates to the output return. Rows 8 and 9 in each column are individually commonly associated with respect to the external output mode.

Field 7 is directed to the start signals. The four columns are associated with the four different control subsystems. External start input signals are related to all of rows 0-3 in each of the different columns, the printed numbers referring to the associated input option position. All of the different columns in row 4 pertain to the respective start panel buttons. Finally, the internal start inputs are applied with respect to all of these columns commonly in each of rows 6, 7 and 8, the printed numbers referring to control subsystems.

Field 8 pertains to reset and stop input with the four columns again associated with respective different control subsystems. Row 12 pertains to the reset panel pushbuttons. Rows 0 and 1 are for selection of internal resets, the printed numbers referring to control subsystems. Rows 2 and 3 are for selection of external reset inputs, the printed numbers referring to reset input option positions. Rows 4 to 9 have the same significance as the similarly marked rows 12, 11 and 0-3 except that they are associated with the stop function.

Field 9 pertains to the external output mode selection. As before, the four columns pertain to the respective different control subsystems. Rows 11 and 0 correspond respectively to the effectively normally closed and normally open positions of circuits-1 of the control subsystems. In a similar manner, rows 2 and 3, 5 and 6 and 8 and 9 represent circuits 2, 3 and 4, respectively.

Finally, field 10 is concerned with the output return to initial mode and with direct inputs and outputs. Rows 12-11 and 0-1 are associated with control subsystems 1 through 4, respectively. The printed numbers in each row refer to the internal output circuits of their respective control subsystems. Rows 2-5 are associated with direct outputs 1-4, respectively. The printed num-

bers in each row refer to the associated direct input option positions.

A more detailed analysis of the different program card governing functions may be of assistance in appreciating more fully the overall principle of operation. As indicated, field 1 governs the selection of the count, clock and event input for control subsystems CS-1. In column 1, rows 0-5 determine the number of events, be they external occurrences or clock units, to be counted by comparison circuit-1 before it provides a count-complete signal. The total count is the sum of the values of all rows punched, where those values for rows 0-5 are 1, 2, 4, 8, 16 and 32, respectively. Accordingly, a total of 63 counts is obtainable from a single circuit in this manner. That may be expanded by the use of other control subsystems to permit a total of 16,777,215 counts for a full system as illustrated. Rows 6-9 govern clock period selection. When control subsystem CS1 is to be operated on a timed basis, the timed period between clocked event inputs may be chosen from the appropriate one of rows 6-9 to be one-sixtieth second, 0.1 second, 1.0 second or 1.0 minute, respectively. Consequently, for a single circuit with the total count of 63, the total time periods for rows 6-9 are one-twentieth second, 6.3 seconds, 63 seconds and 63 minutes, respectively.

In column 3 of field 1, rows 0-5 govern count selection with respect to comparison circuit-2 in the same manner that rows 0-5 of column 1 pertained to that function of circuit-1. Rows 6-9 of column 3 permit selection of which one of up to four available external event inputs is to be counted as an event in control subsystem CS1; it may be noted that either the internal clock, an external event or an internal output may provide the input for an individual control subsystem, but only one may be used at any time. Rows 6-9, therefore, permit the selection of external event input Nos. 1-4, respectively. It may also be noted that an external input may also be used to start and to reset a counting sequence as will be explained further in connection with fields 7 and 8.

Rows 0-5 of column 5 analogously pertain to count selection in comparison circuit-3. Row 6 in this column permits the event panel button to serve as an auxiliary manual input, while rows 7-9 select which one of three available internal outputs is to serve as an event input. That is, rows 7-9 serve to select, as an internal output, the output from circuit-1 of control subsystem CS2, circuit-1 of control subsystem CS3 or circuit-1 of control subsystem CS4, respectively. Next with reference to column 7, once again, rows 0-5 pertain to count selection, in this case determining operation of circuit-4 in control subsystem CS1.

Turning to field 2, it is identical with field 1 if, for every designation of control subsystem CS1 in a function mentioned before, the designation control subsystem CS2 is substituted and certain differences are noted. Columns 9, 11, 13 and 15 correspond to columns 1, 3, 5 and 7 in comparing fields 2 and 1, respectively. In column 13, rows 7-9 pertain to the outputs of the circuit-1 of each of control subsystems CS1, CS3 and CS4, respectively. Row 12 of column 9 permits connecting the output of the counter of control subsystem CS1 to the input of the counter of control subsystem CS2.

Similarly, field 3 is identical to field 1 if the designation control subsystem CS3 is substituted and corre-

ponding differences are noted. In this case, columns 7, 19, 21 and 23 correspond to columns 1, 3, 5 and 7, respectively. In column 21, rows 7-9 serve to permit connection of the output from the circuit-1 of each of control subsystems CS1, CS2 and CS4, respectively.

In the same manner, field 4 is identical with field 1 f, for every designation of control subsystem CS1 in that description, the designation control subsystem CS4 is substituted and the appropriate differences again are noted. Thus, columns 25, 27, 29 and 31 correspond to columns 1, 3, 5, and 7 respectively. Rows 7-9 of column 29 permit internal event input of the output from circuit-1 of each of control subsystems CS1, CS2 and CS3, respectively. Row 12 of column 25 permits connecting the output of the counter in control subsystem CS3 to the input of the counter of control subsystem CS4. In field 4, there is no count carryout, otherwise, row 12 is column 31 could be used for that purpose.

Field 5 enables selection for expandable output system EO1. The selections are the count, the external output mode and an output return to its initial mode. This system is an expansion of control subsystem CS1. In column 33, rows 0-5 permit count selection in a manner entirely analogous to that governed by rows 0-5 in column 1 for field 1. Row 6 in column 33 is denominated output return and permits the output of circuit-4 in expandable output system EO1 to return (reset) the external output of its circuit-1 to its initial mode (normally opened or normally closed). The external output mode selection is controlled by rows 8 and 9 in column 33. This is the controlling signal as seen by the external equipment that is being controlled. By choosing the symbol of row 8 and if, for example, the relay output option has been inserted, the relay contact is normally open and will close when the selected count is reached. The symbol of row 9 is the inverse, normally-closed function.

Rows 0-5 of each of columns 35, 37 and 39 once again govern count selection in the same manner as described above with respect to rows 0-5 of column 1 but in this case respectively with respect to circuit-2, circuit-3 and circuit-4 of expandable output system EO1. Row 6 of each of columns 35 and 37 again is the output return function and respectively enables circuit-2 to be controlled by circuit-4 and circuit-3 to be controlled by circuit-4 in expandable output system EO1. Rows 8-9 of each of columns 35, 37 and 39 again pertain to external output mode selection, respectively of comparison circuits 2, 3 and 4 and all in the manner as described with respect to the same rows in column 33.

Field 6 determines the selection for expandable output system EO2 which is an expansion of control subsystem CS2. This field is identical in function to that of field 5, and the above description of field 5 is applicable to field 6 merely by substituting the designation of expandable output system EO2 for that of expandable output system EO1 in that description.

Field 7 governs selection of the start input. Such an input may be either an external input or an internal output. Column 49 pertains to control subsystem CS1. In column 49, rows 0-3 are used to select one of up to four available external inputs to be used to start the commencement of a sequence. Rows 0-3 thus pertain respectively to external start input Nos. 1-4. Row 4 permits the start panel button to serve as an auxiliary manual input. Rows 6-8 select which one of three

available internal outputs is to serve as a start input, with rows 6-8 respectively selecting the output from the comparison circuit-1 of each of control subsystems CS2, CS3, and CS4, respectively.

5 Columns 51, 53 and 55 similarly govern the start input for control subsystems CS2, CS3 and CS4, respectively. In column 51, rows 6-8 select as an internal output one of the outputs from circuit-1 of control systems CS1, CS3 and CS4, respectively. In column 53, rows 10 6-8 select the output from the circuit-1 of control subsystems CS1, CS2 and CS4, respectively, while in column 55, rows 6-8 select the output from the circuit-1 of the control subsystems CS-1, CS-2 and CS-3, respectively.

15 Field 8 pertains to what may be termed the selection of the cycle reset and the cycle stop inputs. Reset means the resetting of a control subsystem to a zero-count condition, and all outputs to their initial modes. A stop is the termination of the counting cycle or se-

20 quence of a control subsystem, with all outputs remaining in the state in which they were when the stop function occurred. Column 57 relates to control subsystem CS1. In column 57, the symbol of row 12 permits the reset panel button to serve as an auxiliary manual input. Rows 0-1 select which one of two available internal outputs is to serve as a reset input. Rows 0-1 thus permit the respective selection of the outputs from the circuit-2 of control subsystems CS2 or CS3. Rows 2-3 permit selection of two of four external reset inputs.

25 30 Row 4 is used to permit the stop panel button to serve as an auxiliary manual input. Rows 6-7 select which one of two available internal outputs is to serve as a stop input. Thus, rows 6-7 are punched to select the output from the circuit-2 of each of control subsystems CS2-CS3, respectively. Rows 8-9 permit selection of two of four external stop inputs. Columns 59, 61 and 35 63 are identical to column 57 except that they instead control functions of control subsystems CS2, CS3 and CS4, respectively.

40 45 Field 9 is utilized for the selection of the external output mode. Column 65 thus pertains to control subsystem CS1. Rows 11 and 0 govern in comparison circuit-1 of that control subsystem, with rows 11 and 0 being used to choose between the normally-closed and the normally-open modes, respectively. Rows 2 and 3 pertain to the normally-closed and normally-open modes, respectively, of circuit-2. Similarly, rows 5 and 6 enable selection of the respective normally-closed and normally-open modes in comparison circuit-3. Fi-

50 55 nally, rows 8 and 9 respectively choose the normally-closed and normally-open mode as to circuit-4. Columns 67, 69 and 71 are identical to column 54 except that they pertain respectively to control subsystems CS2, CS3 and CS4.

55 60 Finally, field 10 enables selection of the output return to its initial mode whether that be normally open or normally closed. In column 73, the choice of row 12 permits the output of circuit-4 of control subsystem CS1 to return or reset the external output of circuit-1 of control subsystem CS1 to its initial mode. This function may be described as an output return for control subsystem CS1 wherein circuit-1 is controlled by circuit-4. Correspondingly, column 12 in each of rows 75

65 70 and 77 governs the output returns for control subsystem CS1 wherein circuits-2 and -3, respectively, are controlled by circuit-4. Row 11 in each of columns 73, 75 and 77 instead pertains to the output return of con-

control subsystem CS2, with comparison circuits-1, -2 and -3, respectively, being controlled by comparison circuit-4. Row 0 of each of columns 73, 75 and 77 governs the output return for control subsystem CS3 wherein it is comparison circuits-1, -2 and -3, respectively, that are controlled by comparison circuit-4. For row 1 of column 73, 75 and 77, the output return function is associated with control subsystem CS4 and it is comparison circuits-1, -2, and -3, respectively, that are controlled by comparison circuit-4.

Rows 2-5 of columns 73-77 pertain to the selection of direct inputs for direct outputs 1-4 respectively. Row 2 permits selection of direct input 1, 2 or 3 to be connected to direct output 1. Similarly, row 3 offers direct inputs 2, 3 or 4 for connection to direct output 2. Row 4 offers direct inputs 3, 4 or 1 for direct output 3, and row 5 offers direct inputs 4, 1 or 2 for direct output 4.

FIG. 5 thus enables complete determination of all of the different operational functions of a control center which includes all of the different possible subsystems and expansions. As indicated, the card has been pre-printed to facilitate either on-site handpunching or key-punching. In the latter case, an untrained operator may simply follow a pre-prepared diagram. If desired, differently pre-printed cards may be utilized with control centers that contain less than the full complement of subsystems and expandable options. For example, a card for use with a control center that included only one control subsystem would need have no printing in fields 2, 3 and 4 and only the first column utilized in each of fields 7, 8 and 9. In actual practice, all of the different cards to be needed for the possible variations in operation of a given process normally will have been prepared in advance and labeled with a distinguishing designation, e.g., "flow-solder of printed-circuit A-16." With reference to the flow-solder example in the introduction, the line operator encountering a batch of the A-16 boards would then simply pull the appropriate card from an index file and insert it in the card reader of the control center.

In the actual construction of the process control center, a type of modular fabrication preferably is employed in order to facilitate the desired flexibility in numbers of control subsystems, expandable outputs and different options to be employed in any particular installation. Advantage also is taken of present-day technology by incorporating a substantial amount of integrated circuitry and distributing the several different stages and combinations of stages on a plurality of printed-circuit boards. FIG. 6 illustrates, in both block-diagram and functional form, what has been found to be a practical and realistic approach to construction which enables both the desired flexibility and compactness of the ultimate assembly. In FIG. 6, the different card reader connections are represented by the smaller rectangles each of which includes one or more symbols to indicate the function or functions of its particular connections to the card reader. These symbols and their definitions are included in the table at the upper right-hand corner of FIG. 6.

In more detail as to FIG. 6, input terminals 60 connect through input option boards 61 to feed the indicated external input signals to those card reader connections indicated by the rectangle designated IO. Panel buttons 62 connect through a panel switch circuit board 63 both to a card reader connection PS and

to a combined input control and counter board 64. The latter includes both control stages 51 and counter 50 as they were designated in FIG. 3. Card reader connections IC also are fed to board 64. A clock board 65 feeds the several different clock pulses to card reader connections CL and also receives both reset and enable signals from input control and counter board 64. The clock board obtains its base frequency signal from a master oscillator board 65a. The count from board 64 is fed to a comparison circuit board 66 (52 in FIG. 3). The comparison circuit also receives count selection and return selection information from card reader connections CC and CCR as well as the reset signal and a delay signal from input control and counter board 64. In one particular configuration, boards 64 and 66 are combined to form a single primary control subsystem board. From the output of comparison circuit board 66, signals are fed to card reader connections CCI so as to be available as internal inputs. Comparison circuit board output signals also are fed to the normally-closed and normally-opened mode card reader connections CCC and CCO. Signals from the common mode card reader connection OOC are routed through output option boards 68 to output terminals 69. Also, the reset and delay signals as well as a final count signal are supplied to the input control and counter board 70 of the next control subsystem. Appropriate electrical power is supplied to the system by power supply and emergency power modules grouped within a functional block 70a. In operation, the input terminals, panel pushbuttons, clock, internal outputs and outputs from additional comparison circuits and other control subsystems all constitute process-indicating parameters that may be chosen by the card reader. As will be seen in more detail, the individually-different input option boards are each uniquely capable of responding to a particular kind of input signal by producing an initiating signal. The input control and counter board responds to selected different combinations of the input and initiating signals and develops corresponding different control or governing signals that are dependent upon the occurrence of time interval or number of events. Such events may be the passage of units, changes in style or whatever. Responding to selected different combinations of the input signals, the initiating signals and the control or governing signals, the comparison circuit board develops corresponding different process-governing signals that are dependent upon the magnitude of time or number of events. Like the input-options, the output-option boards are each uniquely responsive to the process-governing signals for producing a particular kind of output signal. The card reader and the card inserted therein act as a selectively fixed memory. The latter selection can be made by the key-punch operator, and that person's choice will usually be dictated by a simple diagram, chart or table. The card permits response to chosen combinations of the input signals, initiating signals, control signals, process-governing signals and output signals for determining the development of the initiating signals, control signals, process-governing signals and output signals. Also determined by the memory are the different combinations of signals to be employed at any time. It will be observed that closed loops may be included by means of the card. That is, an output signal may be selected by the card to serve as an input signal. Conversely, an input signal may be routed by the card to serve directly as an output signal. For ex-

ample, the clock signal may be fed directly to an accessory display of the count. In any event, it is the program card which defines both what will happen and when it will happen. The operation of all other basic components of the overall system is essentially dependent upon the information stored in the card.

FIG. 7 represents the state diagram of the input control logic of that portion of board 64. The symbolism employed in FIG. 7 is defined by the inputs and states ables included therein. Thus, FIG. 7 fully defines the digital logic employed. While a person skilled in the art will recognize the availability of a variety of different specific and detailed circuit arrangements for implementing the illustrated input control logic, the description and illustration yet to be presented represent a practical and successful as well as advantageous embodiment.

As will be described in detail in connection with FIG. 16, the inputs listed in the table of FIG. 7 are in the combination of inputs applied to the control 51 portion of board 64, and they are represented in FIG. 7 in terms of function of corresponding ones of the status and command signals by E for event, S for start, R for reset and X for stop. Similarly, the states of control 51, into which operations in control 51 may traverse and reside as defined by FIG. 7 and as implemented in FIG. 16, are represented in FIG. 7 by EC for enable count, DC for disable count and RD for reset count. Following current practice by those skilled in the binary logic art, FIG. 7 also depicts the specific binary nature of the input signals, as implemented in FIG. 16, by use of a 0 for a logical "zero" of "false" signal, a 1 for a logical "one" or "true" signal and a minus (−) sign for a logical "don't care" signal.

FIG. 8 is an interconnection diagram for a process control center which includes a single control system accompanied by one expandable output system. In this case, therefore, fields 2, 3, 4 and 6 of the program card are not utilized. However, the diagram of FIG. 8 may be readily enlarged to include additional control subsystems and a second expandable comparison circuit board by merely adding the corresponding additional fields together with the associated input control and counter boards and comparison circuit boards and wiring these in a manner identical to that for the one control subsystem and expandable output board which have been illustrated in FIG. 8. The different panel switch, display output and output option connection terminals for the added control subsystems already are depicted in this figure.

Thus, the interconnection diagram of FIG. 8 includes input option board 61, panel switches or buttons 63, input control and counter board 64, clock board 65, comparison circuit board 66 and output option board 68 as well as the card reader connection assemblies for fields 1, 5, 7, 8, 9 and 10. Also included is a card reader lock indicator 72, an expandable comparison circuit board 73 and display output terminals 74. In FIG. 8, the connecting lines indicate cables which in many cases include a plurality of connecting wires. In any case, the specific number of wires, in each cable may be determined by reference to the description, e.g., in connection with FIG. 5, of the field or other component to which that particular cable connects. For example, a cable extending from field one to comparison circuit board 66 will thus be found to contain 24 individually different wires. Moreover, a number of the different ca-

bles shown in FIG. 8 have been labeled either with a word denomination of the function carried by that cable or with a symbol which is the same as that defined in the table included in FIG. 6. As noted in connection with control subsystem CS2 of display output board 74, there is an interconnection input which receives a signal from field 2 of the program card that also is fed to the input control and counter board of a second control subsystem when that is included. Similar interconnections will extend to the corresponding fields for control subsystem 3 and 4 when included. These interconnections serve to correlate each successive control subsystem to the preceding one. Other than that, the interconnection diagram of FIG. 8 is self explanatory when considered in light of the previous discussion of the functions implemented by the different rows and columns of the several different fields.

FIGS. 9a, 9b and 9c depict three different input option boards included in the illustrated process control center. In the circuit of FIG. 9a, a neon bulb 100 is connected between terminals A and B through a series resistor 101. Light from bulb 100 irradiates phototransistor 102 which drives an emitter-follower transistor 103. The output signal from transistor 103 is fed through resistors 104 and 105 to the common input of a NAND gate 106 which, together with a second NAND gate 107 and a feedback resistor 108, constitutes a trigger circuit. A load resistor 109 is shunted to ground from the emitter of transistor 103, while a capacitor 110 is shunted to ground from the junction between resistors 104 and 105. From the trigger circuit output, at the output terminal of gate 107, an output signal is supplied to an output terminal 111. From the same source, an inverted output signal is supplied to an output terminal 112 by being fed through a NAND gate 113.

In the input option board of FIG. 9b, a Zener diode has its cathode connected through a resistor 116 to terminal A and its anode connected to ground as well as to terminal B through resistors 117 and 118. The cathode also is shorted to the junction between resistors 117 and 118. The signal appearing at the cathode of diode 115 is fed through a resistor 119 to the common input of a NAND gate 120. The latter, together with another NAND gate 121 and a feedback resistor 122 again is a familiar trigger circuit. Its output signal from the output of gate 121 is supplied to a terminal 123. At the same time, an inverted output signal is supplied to a terminal 124 through an inverting NAND gate 125.

The option board of FIG. 9c is used for a switch or relay type input. Thus, a relay having a center or moveable contact 130, a normally-closed contact 131 and a normally-open contact 132 is illustrated in dashed lines as being connected with those elements extending to terminals G, A and B, respectively. One input of each of a pair of NAND gates 133 and 134 is connected respectively to input terminals A and B, while the outputs of those two NAND gates are cross coupled back to the opposite inputs so as to form a bistable multivibrator. Thus, a positive-going output signal is obtained from the output of gate 134 and presented at an output terminal 135, while the inverse output signal appears at terminal 136 from the output of gate 133.

FIG. 10 is a diagram of the panel pushbutton switch display, the lamp driver circuitry for the push button panel and associated logic boards. Thus, this portion of the system includes panel switches 140, 141, 142 and

143 numbered in correspondence with the layout shown in FIG. 1. Associated with each pushbutton switch is an indicator lamp 144, 145, 146 and 147, respectively. Also included is another indicator lamp 148 which illuminates the subsystem number(s) in use. The normally-closed and normally-open contacts of switch 140 connect individually to one input terminal of each of a pair of NAND gates 150 and 151 with the other input terminals of each of those gates being cross-coupled to the opposite output terminal of the pair of gates so as to form a bistable circuit. The output of gate 150 is connected as one input to a NOR gate 153. The output from gate 153 is then connected to an event output terminal 154. In an identical manner, the fixed contacts of switch 141 are connected to the inputs of a bistable circuit formed of NAND gates 156 and 157 from which a stop signal is derived through a NOR gate 158 and fed to a terminal 159. In the same manner, the fixed terminals of switch 142 are fed to the opposing inputs of still another bistable circuit formed by a pair of NAND gates 160 and 161 with the output of that circuit being fed as an input to a NOR gate 162 and then in series through a pair of open-collector NOT connectives 163 and 164 to a reset terminal 165. A capacitor 166 extends from the junction between the NOT connectives to the ground, while a resistor 167 extends from that junction to a positive voltage source. Similarly, the output of connective 164 is connected through a resistor 168 to a source of positive potential. Finally, and generally in the same way, the fixed terminals of switch 143 are connected to the respective inputs of another pair of NAND gates 170 and 171 again connected as a bistable circuit and with the output of that circuit once more being fed to one input of a NOR gate 171 from the output of which a start signal is fed to a terminal 172.

The other input terminals of each of NOR gates 153, 158, 162 and 171 are connected respectively to an event button select terminal 174, a stop button select terminal 175, a reset button select terminal 176 and a start button select terminal 177. Each of the terminals 174-177 is also connected through respective resistors 178, 179, 180 and 181 to a source of positive potential as well as to the respective inputs of open-collector NOT connectives 182, 183, 184 and 185. The output terminal of each of the latter is connected respectively to one input of a respective one of comparators 188, 189, 190 and 191. The other input terminal of each of those comparators is connected to the output of NOR gates 153, 158, 162 and 171, respectively, with that input for comparator 190 specifically being from the point beyond NOR gate 162 connected to reset terminal 165; each of these later connections is through a respective one of resistors 193, 194, 195 and 196. As illustrated specifically with respect to comparator 188, each comparator includes a first transistor 200 the base of which receives the signal from NOT connective 182, the emitter of which is grounded and the collector of which is connected to one side of indicator lamp 144 through a resistor 201. A load resistor 202 shunts that collector to ground. The other comparator input signal received through resistor 193 is fed to the base of a transistor 205 the emitter of which is connected to ground and the collector of which also is connected in energizing relationship to indicator lamp 144. The other side of indicator lamp 144 is connected to a source of positive potential. Each of the other indicator

lamps 145-147 is similarly driven by its respective comparator circuit. Completing the arrangement of FIG. 10, a cardreader reset terminal 207 is connected to the junction between NOT connectives 163 and 164, while four different pull-up resistors 208, 209, 210 and 211 respectively connect each of the output terminals of NOT connectives 182-185 to a positive source of voltage.

In practice, all of the NAND gates in FIG. 10 are conveniently obtained in integrated circuit form by use of a pair of commercial IC849 integrated circuit packages. Similarly, all of the NOR gates are conveniently packaged in an IC7402 integrated circuit. Finally, the different NOT connectives all are available in one 15 IC7405 hex inverter integrated circuit.

Various of the required voltages and signals are developed by the power supply system of FIG. 11. From the terminals of receptable 45 and by way of main power switch 22, the primary windings of respective 20 12-volt and 24-volt transformers 220 and 221 are energized. Across the secondary windings of these two transformers are respective bridge rectifiers 222 and 223. The rectified output from bridge 222 is connected, over a filter capacitor 225 shunted to ground, 25 to internal terminals 11 and 12 of an IC1723 waveform processor 230.

In FIG. 11, as will be the case in subsequent ones of the other figures, standard integrated circuit packages, such as the IC1723 used in FIG. 11, are incorporated 30 into the circuitry in a manner which, as such with regard to each unit, is conventional and well understood in the art. In the descriptions herein, reference will be made to internally-connecting terminals by means of numbers assigned in specification sheets to MC units.

As well known to the person skilled in the art, the MC 35 designation is one adopted by Motorola, Inc., for its units. Thus an MC1723 is a linear integrated circuit that functions as a voltage regulator, its characteristics being set forth at page 145 in the catalog publication entitled "Master Selection Guide" and "Motorola Semiconductors" and having a 1973 copyright notice. Of course, different manufacturers may assign different internal terminal numbers. However, the functions and manners of connection are now well understood. Thus, 40 a conventional or standard internal terminal 6 is connected through a resistor 231 to ground while an adjustable tap on that resistor is connected to an internal terminal 5. At the same time, an internal terminal 7 is connected to ground while an internal terminal 13 is 45 coupled to ground over a capacitor 232.

The center tap of the secondary winding on transformer 220 is connected, over a capacitor 232 shunted to ground, to the collector of a power transistor 234. Its 50 base is connected to an internal terminal 10 of package 230, while its emitter is connected in common to both internal terminals 2 and 3 of the package. A diode 235 shunts internal terminals 3 and 4, while a Zener diode 236 is connected at its cathode to internal terminal 3 of the package and its anode is connected through a resistor 237 to ground. From the junction between diode 236 and resistor 237, a resistor 238 extends to the base of a transistor 239 the emitter of which is returned to ground and the collector of which is connected to a terminal 240 at which appears an emergency power signal. Internal terminal 4 of package 230 is connected to a terminal 241 at which a positive power potential is presented. An indicator lamp 242, extending from ter-

ninal 241 to ground, indicates the availability of that potential. A resistor 243 also is connected between terminal 241 and the collector of transistor 239. Also from the collector of the latter is a resistor 244 extending to the base of a transistor 245 with a load resistor 246 being connected between the base and the emitter of that transistor. Extending from the collector of transistor 245 is a resistor 247 connected at its other end to the base of still another transistor 249, with its base and emitter being connected through a resistor 250. Its collector is connected to the power source at terminal 241, while its emitter is connected to a terminal 252 on which appears a supply of emergency power. Another filter capacitor 254 is connected between terminal 241 and ground.

One end of bridge 223 is connected to ground while its other or output diagonal corner is connected to the collector of a transistor 260, that collector also being shunted to ground through a capacitor 261. The base of transistor 260 is returned through a Zener diode 262 to ground with that diode also being shunted by a capacitor 263. The base of transistor 260 also is returned to its collector through a resistor 264. From the emitter of transistor 260 and through a diode 266, a 24 volt main power supply is provided at a terminal 267. That terminal is shunted by an indicator light 268 which extends to ground and also is shunted to ground by a filter capacitor 269. By way of another Zener diode 270, the power available at the emitter of transistor 260 is fed through a resistor 271 to the base of a transistor 272 the emitter of which is connected to ground. The junction between diode 270 and resistor 271 is returned to ground through a resistor 273. The collector of transistor 272 is connected to a terminal 275 at which a 24 volt emergency power signal appears, with that terminal also being coupled through a resistor 276 to the internal terminal 4 of package 230. Also from the collector of transistor 272, power is fed through a resistor 278 to the base of transistor 280. The emitter of the latter is coupled to its base through a resistor 281, and that emitter also is connected to the emitter of transistor 245 as well as being returned to ground through another section of main power switch 22. The collector of transistor 280 is connected through a resistor 283 to the base of still another transistor 284 the collector of which is connected to the positive 24-volt power supply terminal 267. The base and emitter of transistor 284 are connected by a resistor 285 and that emitter serves as a source of a 24 volt emergency power by connection to a terminal 286.

The system of FIG. 12 depicts the emergency indicator control system. This system includes a pair of IC74121 monostable multivibrators 300 and 301. Each includes, in the same package, an AND connective and an OR connective preconnected as illustrated. In this case, an emergency reset terminal 302 is connected to an internal terminal 3 of package 300 and specifically to the OR connective. A power source terminal 304 is connected through a resistor 305 to the internal terminals 4 and 5 of both packages 300 and 301. A power source is also connected from a terminal 307 through a resistor 308 directly to an internal terminal 11 and through a capacitor 309 to an internal terminal 10 of package 300. From an internal terminal 6 of that package, a connection extends through a diode 310 and a resistor 311 to the base of a transistor 312 the emitter of which is returned to ground and the collector

of which is connected through an emergency reset indicator light 313 to a 24-volt power terminal 314. A resistor 315 is connected between the collector of transistor 312 and ground, while a diode 316 extends from terminal 302 to the junction between diode 310 and resistor 311.

The emergency stop circuitry is essentially identical. Thus, an emergency stop signal appearing at a terminal 320 is fed to internal terminal 3 of package 301 and an output signal from internal terminal 6 of that package is fed through a diode 321 and a resistor 322 to the base of a transistor 323 the emitter of which is connected to ground and the collector of which is connected through an emergency stop indicator light 325 to a 24 volt power terminal 326. A resistor 327 is connected between the collector of transistor 323 and ground, while a diode 328 is connected from terminal 320 to the junction between diode 321 and resistor 322. Power is supplied from a terminal 330 through a resistor 331 directly to an internal terminal 11 and over a capacitor 332 to an internal terminal 10 of package 301.

The emergency reset signal derived through diode 310 is fed through another diode 336 and a resistor 337 to the base of one transistor 338 in a differential amplifier that includes a balancing transistor 339. At the same time, the emergency stop signal from an internal terminal 6 of multivibrator package 301 is derived at the output side of diode 321 and fed through another diode 340 and resistor 337 also to the base of differential transistor 338.

A low-voltage emergency power signal appears at a terminal 342 and is fed through a resistor 343 to the base of a transistor 344 the emitter of which is returned to ground. The collectors of both transistors 344 and 348 receive energization through a resistor 349 connected to a terminal 350 at which the low-voltage power supply appears. Those collectors also are connected in common to the base of a further transistor 352 which has its emitter returned to ground. Its collector is connected through a resistor 353 to the base of differential transistor 339 in order to drive the latter. The collectors from each of differentially-connected transistors 338 and 339 are commonly connected 45 through a sound generator 355 to a terminal 356 at which the 24 volt power supply appears. Thus, any unbalance caused in the operation of the differential transistors 338 and 339 as a result of the current of any emergency signal results in the development of an audible alarm.

As still another emergency indication, a one pulse-per-second signal, appearing at terminal 358, is fed through a resistor 359 to the base of a transistor 360 the emitter of which once again is connected to ground. Its collector drives the base of a transistor 361 through a resistor 362, the emitter of transistor 361 being returned to ground. The resulting signal at the collector of transistor 361 is connected through an emergency power indicator lamp 364 to terminal 365 on which appears 24-volt power. Completing the overall arrangement is a load resistor 366 connecting the collector of transistor 361 to ground and a resistor 367 connected between a terminal 368, at which the low voltage appears, and the collectors of both transistors 352 and 360. Also, a jumper 370 may be connected, when desired, between the base of transistor 338 and ground in order to disable the sound-alarm portion of the system.

FIG. 13 includes the reader lock circuitry. The input to the reader lock network appears at a terminal 372 and is fed in common to the input terminals of each of open-collector NOT connectives 373, 374, 375, 376 and 377. The output signals from each of connectives 374-377 connect respectively to the corresponding terminals 378, 379, 380 and 381 of the four different control subsystems CS1 through CS4. On the other hand, the output signal from connective 373 is fed to the base of a transistor 383 the emitter of which is connected to ground and the collector of which is connected through a resistor 384 to the base of a transistor 385 again having its emitter connected to ground. The collector of transistor 385 is connected through an unlocked indicator lamp 386 to a 24 volt power terminal 387. On the other hand, the collector of transistor 383 is connected through a locked indicator lamp 388 to a 24 volt power terminal 389. Completing the circuitry, a load resistor 390 connects the collector of transistor 385 to ground, a load resistor 391 connects the collector of transistor 383 to ground and the base of transistor 383 is connected to a low-voltage source of power through a resistor 392.

FIGS. 14a through 14d depict the various different types of output option boards. FIG. 14a represents the transistor switch option board that supplies a D.C. signal. The common mode signal is fed through a resistor 400 to the base of a transistor 401 the emitter of which is returned to ground. A signal from the collector of transistor 401 is fed through a resistor 402 and a resistor 403 to the base of a transistor 404 from the collector of which the output signal is supplied to the appropriate rear panel terminal A. The collector of transistor 404 also is returned to ground through a load resistor 405, while the 24 volt DC power source at input terminal 2 is connected to the emitter of transistor 404 and through a resistor 406 to the junction between resistors 402 and 403. In this case, the rear panel terminal B is grounded.

A silicon-controlled-rectifier trigger transformer option board is shown in FIG. 14b. Here, the common-mode signal is fed through a resistor 410 to the base of a transistor 411 the emitter of which is returned to ground at input terminal 5. The collector is connected through a resistor 412 and the primary winding of a transformer 413 to the 24 volt power source at input terminal 2. The secondary winding of transformer 413 is connected between rear panel terminal C, the SCR cathode connection, and rear-panel terminal A which is to be connected to the gate of the external SCR. As indicated, the transformer winding polarities are inverted.

Serving as a relay option board is the circuit of FIG. 14c. Thus, a common-mode signal again is connected through a resistor 415 to the base of a transistor 416 which has its emitter returned to ground at input terminal 5. The collector of transistor 416 is connected through a solenoid winding 417 to the 24 volt power source at input terminal 2. Solenoid winding 417 is shunted by a diode 418. Fixed normally-closed contact 419 is connected to the appropriate rear panel terminal C, while fixed normally-open contact 420 is connected to the corresponding rear panel terminal A. Center terminal B of the same rear panel connector is wired to the center of moveable contact 421 of the relay.

In the logic output option board of FIG. 14d, the common-mode signal from input terminal 3 is again fed

through a resistor 423 to the base of a transistor 424 which has its emitter returned to ground at input terminal 5. The signal from the collector of transistor 424 is fed directly to the base of a transistor 425 from the collector of which the output signal is fed to rear panel terminal A. 24 volt power is supplied from input terminal 2 through a resistor 427 and a resistor 428 to the collector of transistor 424, while a division of the supply power is connected from the junction between resistors 427 and 428 directly to rear panel terminal C and through a resistor 429 to the collector of transistor 425. A Zener diode 430 is shunted between the last-mentioned junction and ground, while the rear panel terminal B is grounded.

Turning to the clock board of FIG. 15, a pilot power signal is fed from a terminal 440 through the series combination of a diode 441 and a resistor 442 directly to one input terminal of a NAND gate 443 and through a diode 444 to the other input terminal of that NAND gate. A resistor 445 and a Zener diode 446 are each shunted to ground from the junction between resistor 442 and the first-mentioned input terminal of gate 443. To form a bistable circuit, the output terminal of gate 443 is connected to one input of a NAND gate 448 which has its output terminal returned through a resistor 449 to the second-mentioned input terminal of gate 443. From gate 448, a signal is fed through a NOT connective 450 to an output terminal 451 at which the one-sixtieth second clock pulse appears.

A reset signal (resets on "zero") from the input circuit board and appearing at a terminal 452 is fed to one input of a NAND gate 453, while the enable signal from the same source and of the same form which appears at an input terminal 454 is fed to an input terminal of a second NAND gate 455. Gates 453 and 455 are cross-connected between their other input terminals and the opposite output terminals so as to form a bistable circuit. The remainder of the clock is composed primarily of standard integrated-circuit counters. It thus includes a pair of IC7492 divide-by-six counters 460 and 461 and a pair of IC7490 decade or divide-by-ten counters 462 and 463. The detail characteristics of these units are set forth at page 111 of the aforesaid "Master Selection Guide." The output from gate 453 is connected to internal terminals 2 and 3 of both decade counters 462 and 463 as well as to the internal terminals 6 and 7 of counters 460 and 461. The output from gate 455 of the one bistable circuit serves as an input to gate 448 and the output from that gate is fed to internal terminal 1 of counter 460. From internal terminal 8 of the latter, an output signal is derived through a NOT connective 465 and presented at a terminal 466 as the 0.1 second count. Internal terminal 8 of counter 460 also drives counter 10 by connection to internal terminal 14 thereof so as to develop at its internal terminal 11 a 1-second count which is fed to a terminal 468 through a NOT connective 469. That count also is supplied as an input to counter 463 at its internal terminal 14 and, thereby, develops from its internal output terminal 11 an optional ten second counting pulse which is fed through a NOT connective 470 to an output connection 471. The output signal from counter 463 also is fed to the input internal terminal 1 of counter 461 so as to develop from its output at internal terminal 8 a 1-minute count pulse which is fed through a NOT connective 472 to an output terminal 473. Completing the arrangement, internal terminals 6 and

7 of counters 462 and 463 and internal terminals 14 of counters 460 and 461 are connected to ground, while terminals 1 and 12 of each of counters 462 and 463 are connected together. The input to the clock board, terminal 440, is obtained from a master-oscillator that provides a signal at a base frequency. In the implementation described, this oscillator has a free-running frequency of about 60 Hertz. Further, it is synchronized to the standard power line frequency of 60 Hertz. In the event of power-line failure, it can still provide a reasonably accurate base frequency signal when using battery power.

At the heart of the process control center in each subsystem is the input control and counter board of FIG. 16. With respect to reset (on "one"), terminals 480, 481 and 482 are presented with those signals respectively from the corresponding panel switch, control input and emergency input. Similarly, terminals 483, 484, and 485 receive the stop (on "one") signals from the panel switch, control input and emergency input, respectively. Terminals 486 and 487 respectively receive the start signals (on "one") from the panel switch and control input. Finally, terminals 487 and 488 receive event or clock signals (on "one") from the panel switch or control input, respectively. Other terminals provide interconnection from a previous control subsystem. These include the Q_5 final count signal at terminal 489, the reset signal at terminal 490, the delay signal at terminal 498 and the count interconnect at terminal 492.

The output terminals include a reset terminal 494 which connects to the comparison circuit board and an inverted reset terminal 495 which connects to the clock board, the input board of the next subsystem and a counter display option. An enable signal which appears at a terminal 496 is connected to the clock board of control subsystem CS1. A delay signal, which is fed to the comparison circuit board as well as to the input board of the next subsystem, appears at a terminal 497. A display event signal, which is fed to an accessory counter display, appears at a terminal 491, while a complementary display event signal appears at a terminal 499. Finally, this system includes counter output terminals $Q_0 - Q_5$ which connect to the comparison circuit board as well as to the external output terminals. Terminal Q_5 also is connected to the input board of the next subsystem.

Terminals 480, 481 and 482 are each connected through respective open-collector NOT connectives 500, 501 and 502 to one input of a first NAND gate 504 and to one input of a binary circuit composed of a pair of cross-connected NAND gates 505 and 506. The other input of the latter binary circuit is connected to the output of NAND gate 504. The common connection from the output of connectives 500-502 also is connected to one input of a NAND gate 507 the output of which is connected to a first input of another binary circuit again composed of a pair of NAND gates 508 and 509. The signals from input terminals 483-485 are fed through respective open-collector NOT connectives 510, 511 and 512 from the common outputs of which one connection is direct to a second input of gate 504 and another connection is through a NOT connective 515 to a third input of gate 507.

Start signals on terminals 486a and 486b are fed to the respective inputs of an OR connective 516 the output of which is connected as a third input to gate 504.

The output of gate 506, and thus of that binary circuit, also is connected back as an additional input to both of gates 507 and 509. Event or clock signals appearing at input terminals 487 and 488 are fed to the respective inputs of an OR connective 520 the output of which is connected to the internal terminal 5 of a monostable multivibrator 521 which, as in FIG. 12, preferably is an IC74121 integrated circuit. Its internal input terminal 4 is connected to ground and a source of positive potential is connected through a resistor 522 directly to internal terminal 11 and through a capacitor 523 to internal terminal 10. One output from internal terminal 1 of multivibrator 521 is fed to a first input at internal terminal 4 of a second monostable multivibrator 525. Its other trigger input terminal 3 is connected to receive the bistable signal at the output of gate 506. Multivibrator 525 is energized directly at its internal terminal 11 through a resistor 526 from a source of positive potential and through that same resistor over a capacitor 527 to internal terminal 10.

Included in the output portion of the circuitry in FIG. 16 are a plurality of AND gates 530, 531, 532, 533, 534 and 535. The bistable signal at the output of gate 506 is fed to one input of a NAND gate 537 the other input of which is connected to receive the other bistable signal at the output of gate 509. An enable signal from the output of gate 537 is fed directly to output terminal 496 and, through a NOT connective 538, to an input of gate 532. The other output from internal terminal 6 of multivibrator 521 is fed to an input of gate 534, while the output from internal terminal 1 of multivibrator 525 is fed to an input of gate 532. The delay signal from input terminal 498 is fed to an input of gate 533, while the interconnection signal from terminal 492 is fed directly to another input of gate 534 and also through a NOT connective 540 to an input of each of gates 535, 533 and 531. The interconnection signal from terminal 492 also is fed directly to an input of gates 530 and 532. The Q_5 input signal at terminal 489 is connected to another input of gate 535.

From the outputs of gates 530 and 531, the respective signals are fed to the two different inputs of an OR connective 544 from the output of which a negative-going reset signal appears at terminal 494 and, through a NOT connective 545, an inverted reset signal appears at terminal 495. The signal from the output of gate 532 is fed through a NOT connective 547 to one input of an OR connective 548 the other input of which receives the output signal from gate 533. The output from connective 548 is the delay signal which is applied to output terminal 497. The outputs from each of gates 534 and 535 serve respectively as the inputs to an AND gate 550 from the output of which the display event complement appears directly at terminal 499. Through a further NOT connective 552, the direct display event signal is applied to terminal 491 and also is fed to an internal terminal 14 of a counter 560.

The counter itself features a four-bit binary counter 560 and a pair of JK flip-flops 561 and 562. Conventionally, counter 560 is a type IC7493 integrated circuit, while flip-flops 561 and 562 are both contained in an IC7473 integrated circuit. The reset signal at terminal 495 is fed to the common input connection of the AND gate 560a integrally associated with counter 560. That same reset signal also is fed through a resistor 562 to the base of a transistor 563 the emitter of which is returned to ground. The signal from its collector is fed

as an input to respective internal terminals 2 and 6 of flip-flops 561 and 562. The signal at output terminal 11 of counter 560 is connected as an output to terminal Q₃ and as an input to internal terminal 1 of counter 561. The output signal from the latter counter, which appears at its internal terminal 12, is utilized as an output signal at terminal Q₄ and also as an input to internal terminal 5 of flip-flop 562. From internal terminal 9 of the latter, the final count signal is derived and applied to terminal Q₅. Count output terminals Q₀, Q₁ and Q₂ are connected respectively to internal terminals 1, 9 and 8 of counter 560. Finally, a positive source of power is connected to terminals 3 and 14 of flip-flop 561, terminals 7 and 10 of flip-flop 562, and to terminal 5 of multivibrator 525. This particular source of power V_h is derived through a resistor 566 from a stable power source V_{cc}. The latter also is connected through a resistor 567 to the input side of NOT connective 540 in order to supply power to the various different associated AND gates. Also, power is supplied from source V_{cc} to NOT connectives 500-502 and 510-512 through resistors 570 and 571, respectively.

In practice, all of connectives 500-502 and 510-512 may be contained in one IC7405 integrated circuit. OR gates 516, 520, 544 and 548 similarly may be combined in an IC3003 integrated circuit. All of the different NOT connectives are obtained in a single IC7404 integrated circuit. The triple-input NAND gates 504, 507 and 509 are conveniently combined in a first IC7410 integrated circuit, while the similar gates 532, 534 and 535 are combined in another one of the same integrated circuits. The dual-input NAND gates 505, 506 and 508 likewise are conveniently found in a combined form in an IC7400 integrated circuit. AND gates, 530, 531, 533 and 550 all may be included as a package represented by a single IC3001 integrated circuit.

Finally, attention is directed to the comparison circuit board of FIG. 17. Along the top of the drawing are the six different terminals Q₀-Q₅ which receive the count output from the counter board. The different switch mode output terminals appear along the right-hand edge of the drawing with each pair including an upper terminal, such as CCC1, which is the normally-closed output signal, and a second CCO terminal at which the normally-open switch mode signal appears. Associated with each such pair of switch-mode output signals (each of which individually is fed to a corresponding card reader connection) is a type-D flip-flop conveniently of the IC7479 type. These appear as flip-flops 600, 601, 602 and 603. The delay signal is applied in each case to one input of a respective one of AND gates 604, 605, 606, and 607. The other input signal to each of those AND gates is the normally-open output signal from its associated flip-flop. Thus, internal terminal 6 of flip-flop 600 is connected as an input to gate 604, while internal terminal 5 serves to deliver the normally-closed output signal. The output from gate 604 is fed to internal terminal 3 of flip-flop 600. Also associated with each of the flip-flops is the respective one of NOR gates 610, 611, 612 and 613. The output from each of these NOR gates is fed to a reset input of its associated flip-flop. Thus, the output from gate 610 is fed to internal terminal 1 of flip-flop 600. An input of each of gates 610-613 is the reset signal. The other input of gate 613 is connected to ground, while the other inputs of gate 610, 611 and 612 are connected to receive the

return-to-initial-mode selection signals CCR1, CCR2 and CCR3, respectively.

The remainder of the comparison board of FIG. 17 is a matrix of exclusive NOR gates. In each column, one input of all of the exclusive NOR gates is connected to receive the corresponding count output signal from the input circuit board. Thus, the column of gates 620, 621, and 622 and 623 each receive as an input signal the Q₅ count through a NOT connective 624. The other input to each of those exclusive NOR gates in that column is individually connected to respective different card-reader count selection terminals 626, 627, 628 and 629. Each of these latter connections is also connected to a common source of power potential through respective isolating resistors 630, 631, 632 and 633. Exclusive NOR gate 620, then, is also associated with a row that includes the additional exclusive NOR gates 640, 641, 642, 643 and 644. Each of these additional exclusive NOR gates is connected in its column in the same way as described with respect to gate 620. Moreover, all of the gate outputs in each row are connected in common to the D-input terminal of the flip-flop associated with that row. Thus, the outputs of gates 620 and 640-644 all are connected to internal terminal 2 of flip-flop 600. Finally, it is also to be noted that the common output in each row also is available at a CCI terminal as an available internal input.

Of course, suitable DC power connections also are made. Thus, a source of positive potential V+ is connected through a resistor 650 to the output terminals of each of the exclusive NOR gates and the same source also is connected to the set terminal such as internal terminal 4 of flip-flop 600. Also, using the IC7479 flip-flop, its internal terminal 14 is connected, as is conventional, to an appropriate positive potential and its internal terminal 7 is connected to ground. Each different column of exclusive NOR gates is conveniently contained in an IC7242 integrated circuit, the AND gates are likewise all contained in a single IC3001 package, the NOR gates similarly are packaged together in an IC7402 integrated circuit and the NOT connectives or inverts are conveniently found together in an IC7404 integrated circuit.

While much of the circuitry in the process control center may seem, at first glance, to involve highly complex and sophisticated arrangements, it may be observed upon reflection that practical complexity is substantially reduced through the judicious incorporation of numerous off-the-shelf commercially-available integrated circuits. The ultimate result is a system which enables a digital-type computer control while yet avoiding completely the need for peripheral or interface equipment. More particularly, once schedules have been prepared to enable punching of the program cards, no experience is necessary in order actually to prepare those cards and no technical experience whatsoever is needed by the line operator actually supervising the process under control. Although a standard computer program card has dimensions only slightly larger than 3 x 7 inches, advantage is taken of half of its eighty normal columns and of most parts of all of its twelve rows to achieve several hundred different possible bits of information available for storage on any given card. Thus, a maximum degree of flexibility is afforded in what in many ways is a very straight-forward approach.

As such, card reader 20 is disclosed and claimed in co-pending divisional application Ser. No. 461,110, filed Apr. 15, 1974, and assigned to the same assignee as the present application.

While particular embodiments of the present invention have been shown and described, it is apparent that changes and modifications may be made therein without departing from the invention in its broader aspects. The aim of the appended claims, therefore, is to cover all such changes and modifications as fall within the true spirit and scope of the invention.

I claim:

1. A programmable process and production control center for operating a system which system yields process and production status signals, said control center being subject to the receipt of command signals from source means external to said control center, with said control center comprising:

comparison means for developing an output signal in response to a first combination of input signals and to governing signals;

means for producing said governing signals to govern the operation of said comparison means in response to a second combination of input signals; and selectively-fixed totally-and-simultaneously-

accessed passive self-decoding read-only memory means responsive to a plurality of incoming signals for defining and determining the development of said first and second combinations of input signals, said incoming signals being a combination of those present of said status signals, of said command signals, of signals representing a time interval, of signals representing a number of events and of signals, including said governing signals and said output signal, representing said governing operation,

said memory means including a medium in which is defined an array of signal path locations that define and represent a program and also including a reader for said medium to accept and translate array-defined ones of said incoming signals as input signals of said first combination to which said comparison means responds and to accept and translate array-defined ones of said incoming signals as inputs signals of said second combination to which said producing means responds with said second combination of input signals including signals representing the magnitude of at least one of said time interval and said number of events, the program defined and represented by said array determining which of said incoming signals are translated as input signals and also determining at least in part which of said incoming signals are included in each of said first and second combinations of input signals,

and said read-only-memory means exhibiting a self-contained capability of responding directly to all possible combinations of said incoming signals in definition and determination of said development.

2. A control center as defined in claim 1 which further includes means for receiving direct external control signals and means responsive through said memory to said direct external control signals for presenting said external control signals as additional output signals exclusive of operation thereon by said comparison means and said producing means.

3. A control center as defined in claim 1 which further includes both a normal power supply and an auxili-

ary power supply and which still further includes means responsive to failure of said normal power supply for enabling operation of said auxiliary power supply automatically for a fail-safe time period.

4. A control center as defined in claim 1 in which said producing means includes a master clock together with means responsive thereto for developing a plurality of respectively different clock increment signals, and in which said clock increment signals are selectively supplied to said producing means by said memory means as input signals in said second combination.

5. A control center as defined in claim 1 which includes means for feeding said output signal to said memory means as an additional incoming signal.

6. A control center as defined in claim 1 which includes a plurality of said comparison means each responsive, in response to selective definition and determination by said memory means, to a first combination of input signals and to governing signals for developing an output signal.

7. A control center as defined in claim 1 which further includes a plurality of individually different input-option circuits each uniquely responsive to a particular and respective different kind of status signal for developing an incoming signal.

8. A control center as defined in claim 1 which further includes a plurality of individually different output-option circuits each selectively chosen by said memory means and each uniquely responsive to output signals for developing a particular and respective different type of externally-available outgoing signal.

9. A control center as defined in claim 1 which includes a plurality of said producing means each individually responsive under definition and determination by said memory means, to respective array-defined second combinations of said input signals for developing respective corresponding different governing signals.

10. A control center as defined in claim 9 in which successive different ones of said producing means individually respond, under definition and determination by said memory means, to an output signal produced by a comparison means associated with a preceding one of said producing means.

11. A control center as defined in claim 1 in which said medium is a planar card of insulating material and said array is a pattern, in rows and columns, of positions at each individual one of which positions a respective aperture in said card may be formed as selectively chosen by the user.

12. A programmable process and production control center for operating a system which system yields process and production status signals, said control center being subject to the receipt of command signals from source means external to said control center, with said control center comprising, in a unitary combination:

means for providing a plurality of individually different ones of said status and command signals; means, including a plurality of individually different input-option circuits each uniquely responsive to a particular kind of said status and command signals, for developing a plurality of respectively different initiating signals;

means, including an input control and counter system, responsive to combinations of said different initiating signals for developing correspondingly different control signals;

governing means, including a comparison circuit, responsive to combinations of said different initiating signals and said control signals for developing correspondingly different process-governing signals; means, including a plurality of individually different output-option circuits each uniquely responsive to said process-governing signals, for developing a plurality of respectively different particular types of output signals; 5 and means, including a self-contained selectively-fixed totally-and-simultaneously-accessed passive self-decoding read-only memory, responsive directly to combinations of incoming signals for defining and determining the development of combinations of input signals including said combinations of signals and which ones of said input-option and output-option circuits are connected, 10 said combinations of incoming signals being combinations of those present of said initiating signals, said control signals, said process-governing signals 15 and said output signals, 20 said combinations of input signals being combinations of those present of said initiating signals, said control signals, said process-governing signals and said output signals, 25 said memory including a medium in which is defined an array of signal path locations that define and represent a program and also including a reader for said medium to accept and translate array-defined ones of said incoming signals as input signals of said 30 combinations of said input signals with said combinations of signals to which said governing means responds including signals representing the magnitude of at least one of a time interval and a number of events, the program defined and represented by 35 said array determining which of said incoming signals are translated as input signals and also determining at least in part which of said incoming signals are included in each of said combinations of input signals as well as selecting the particular signals in each of the respective combinations to which said developing means and said governing means respond while simultaneously connecting said ones of said input-option and output-option 40 circuits. 45

13. A programmable process and production control center for operating a system which system yields process and production status signals, said control center being subject to the receipt of command signals from source means external to said control center, with said 50

control center comprising, in a unitary combination: means for providing a plurality of individually different ones of said status and command signals; first option means responsive to a particular kind of said status and command signals for developing a plurality of respectively different initiating signals; means, including an input control and counter system, responsive to combinations of said different initiating signals for developing correspondingly different control signals; governing means, including a comparison circuit, responsive to combinations of said different initiating signals and said control signals for developing correspondingly different process-governing signals; second option means responsive to said process-governing signals for developing a particular type of output signal; and means, including a self-contained selectively-fixed totally-and-simultaneously-accessed passive self-decoding read-only memory, responsive directly to combinations of incoming signals for defining and determining the development of combinations of input signals including said combinations of signals, 25 said combinations of incoming signals being combinations of those present of said initiating signals, said control signals, said process-governing signals and said output signals, 30 said combinations of input signals being combinations of those present of said initiating signals, said control signals, said process-governing signals and said output signals, 35 said memory including a medium in which is defined an array of signal path locations that define and represent a program and also including a reader for said medium to accept and translate array-defined ones of said incoming signals as input signals in said combinations of input signals with said combination of signals to which said governing means responds including signals representing the magnitude of at least one of a time interval and a number of events, the program defined and represented by 40 said array determining which of said incoming signals are translated as input signals and also determining at least in part which of said incoming signals are included in each of said combinations of input signals as well as selecting which of said signals are included respectively in said combinations of said different initiating signals. *
